UNITED STATES PATENT OFFICE.

ARTHUR S. HUGHES, OF MINDEN, LOUISIANA, ASSIGNOR OF SEVEN-TWENTIETHS TO
DR. JOHN B. BENTON, OF MINDEN, LOUISIANA.

RAIL ADJUSTER.

Application filed October 13, 1927. Serial No. 226,031.

The present invention relates to improvements in rail adjusters and has for an object to provide an improved compact device for quickly and efficiently adjusting relatively 5 the ends of adjacent railway rails.

Another object of the invention is to provide a relatively inexpensive device for adjusting rails in which the great number of workmen now required will be dispensed 10 with and the work carried out at a minimum of expense.

The further object of the invention is to provide an improved rail adjuster in which the time element heretofore required for carrying out this work will be greatly diminished, and in which the labor charge will be proportionately reduced.

With the foregoing and other objects in view, the invention will be more fully described hereinafter, and will be more particularly pointed out in the claims appended hereto.

In the drawings, wherein like symbols refer to like or corresponding parts throughout the 25 several views—

Figure 1 is a top plan view, with parts broken away and parts in section, of an improved rail adjuster constructed according to the present invention.

Figure 2 is a side elevation of the same.

Figure 3 is a cross section taken on the line 3—3 in Figure 1, and

Figure 4 is also a cross section taken on the line 4—4 in Figure 1.

Referring more particularly to the drawings 5 and 6 designate the adjacent ends of two railway rails to which the adjusting device is applied. The device shown generally is composed of a pair of heads 7 and 8, each 35 traversed by two threaded bores which are offset to opposite sides of the central portions of the heads and which are adapted to receive the pair of screw shafts or rods 9 and 10. Each shaft or rod is provided with 40 both right and left threads, the right threads extending from one end to approximately the central portion while the left threads extend from the opposite end approximately to the central portion. The bores of the heads 45 are threaded to correspond with the shaft ends engaging same, the object being to draw the heads 7 and 8 together or toward one another upon rotation of the screw shafts in one direction, and to cause the heads to move 50

apart when the shafts are rotated in the opposite direction.

The central under portions of both heads are cut away to receive the balls of the two rails 5 and 6. Each head at one side, as shown in Figures 3 and 4, is provided with a shallow recess 11 cut in from the shoulder 12 which engages beneath the ball of the rail. At the opposite side of each head a deeper recess 13 is provided and the underline or shoulder portion 14 is cut away and is more remote from the rail. As shown at the left of Figure 1 the recess 13 is provided with an inner wall having the inclined portions 15 and 16 meeting centrally in the apex 17 and sloping in opposite directions away from the rail. These inclined faces or walls 15 and 16 are adapted to receive thereagainst the inclined rear walls 18 of wedge blocks 19 having teeth along their forward surfaces for engaging against the side of the ball of the rail.

Appropriate means may be employed to rotate the screw shafts 9 and 10 and for this purpose a pawl and ratchet arrangement is shown as engaged with each of the shafts. The ratchet wheel is indicated at 21 being 60 fixed to each screw shaft as by the key 22. The external teeth 23 upon the ratchet wheel are arranged to be engaged by either end 24 or 25 of the double pawl or dog, which is pivoted centrally at 26 within the operating 65 socket member adapted to receive the handle indicated at 28 in dotted lines. The socket member 27 is provided with the bifurcated spaced arms 29 and 30 having coaxial openings to engage about the smooth bearing surfaces 31 and 32 upon the shafts at opposite 70 sides of the ratchet wheels.

In the use of the device, the adjuster is applied to the rails as shown in the drawings with the heads 7 and 8 saddled upon the two 75 rails 5 and 6 near the ends thereof. As shown in Figure 4, the heads are so disposed upon the rails that the shoulder 12 will hook under the balls at one side of the rail to keep the adjuster device in place and to avoid its raising off the rail. The wedges 19 may be applied as shown in Figure 1 to the outside inclined walls 15 or they may be applied to the near or inner inclined walls 16. In order to push the rails with the adjuster, the wedges are inserted as shown in Figure 1, that is from the outside of the heads. The wedges are tightened by giving to the jack 80 85 90 95 100 105

screws or screw shafts 9 and 10 several oscillations. When it is desired to pull the rails, the wedges are released by operating the jack screw in the opposite direction and subsequently removing the wedges 19 from the outside, and inserting them on the inside walls 16. Several movements of the jack screws in the proper direction will tighten the wedge in this new location and the work of pulling the rails may then be carried out by the continued rotation of the jack screws by the pawl and ratchet device. This is accomplished by repeatedly oscillating the handles 28. The wedges may be secured to the adjuster by means of chains to prevent loss. When the wedges are removed entirely from the heads, the device may be slid along the rails to the new location required.

When the rails become lapped, put the adjuster on the joint affected, and insert one wedge from the outside of the head that is on the stationary rail, and let the other head of the adjuster bear against the end of the rail that is to be pushed back into place, leaving the wedge out. The head then travels loose on the rail, pushing the displaced rail back to its proper place.

There are no bolts or nuts or rods to adjust or tighten in the improved adjuster, and a single person may operate same, doing away with the large number of workmen now employed in road gangs rendering the adjustment of rails possible at very small expense as compared with the old method.

It will be obvious that many changes in the construction, combination and arrangement of parts could be made, which could be used without departing from the spirit of my invention, and I do not mean to limit the invention to such details, except as particularly pointed out in the claims.

Having thus described my invention, what I claim and desire to secure by Letters Patent of the United States is:—

1. An improved rail adjuster comprising spaced heads for engaging the rails and having cut away portions to receive the rails with shoulders at one side to hook under the balls of the rails, the other sides of the heads being provided with divergent inclined walls, wedges for removably engaging either of the

inclined walls and the rail balls, and means for moving said heads together or apart.

2. An improved rail adjuster comprising spaced heads for engaging the rails and having cut away portions to receive the rails with shoulders at one side to hook under the balls of the rails, the other sides of the heads being provided with divergent inclined walls, wedges for removably engaging either of the inclined walls and the rail balls, and screw shafts engaging the heads for moving the same together and apart.

3. An improved rail adjuster comprising spaced heads for engaging the rails and having cut away portions to receive the rails with shoulders at one side to hook under the balls of the rails, the other sides of the heads being provided with divergent inclined walls, wedges for removably engaging either of the inclined walls, and the rail balls, differential screw shafts engaging through the heads for moving the same together and apart, and means for rotating said screw shafts in either direction.

4. An improved rail adjuster comprising spaced heads for engaging the rails and having cut away portions to receive the rails with shoulders at one side to hook under the balls of the rails, the other sides of the heads being provided with divergent inclined walls, wedges for removably engaging either of the inclined walls and the rail balls, screw shafts having right and left threads engaging through said heads, and oscillating means for rotating the heads in either direction.

5. An improved rail adjuster comprising spaced heads for engaging the rails and having cut away portions to receive the rails with shoulders at one side to hook under the balls of the rails, the other sides of the heads being provided with divergent inclined walls, wedges for removably engaging either of the inclined walls and the rail balls, screw shafts for engaging said heads, ratchet wheels secured to said shafts, socket pieces having perforated bifurcated arms straddling said ratchet wheels and bearing on smooth portions of the screw shafts, and double ratchets carried by said socket pieces for engaging the teeth of the ratchet wheels.

ARTHUR S. HUGHES.
